UNITED STATES PATENT OFFICE.

JAKOB MULDER AND DIRK CHRISTIAAN ENDERT, JR., OF ROTTERDAM,
NETHERLANDS.APPARATUS FOR REMOVING LIQUID RESIDUES FROM TANKS, PIPE SYSTEMS, AND
THE LIKE.

Application filed November 23, 1926, Serial No. 150,362, and in Germany November 23, 1925.

This invention refers to apparatus for removing liquid residues from tanks, pipe systems and the like such as petroleum and benzine.

5 In most tank ships for carrying oils and the like, it often occurs that after the liquid has been removed from the tanks by pumps, owing to the slightly slanting position of the ship, the suction mouth of the suction pipe 10 becomes obstructed by the residues of the liquid left behind.

There are but few tank-ships which are so well equipped that these final oil or benzine residues can be removed by means of the 15 pumps. It is, therefore, necessary in such cases to wait until these benzine residues have been vaporized or else the liquid must be removed by means of buckets. In either case the process is laborious and in the latter case 20 even dangerous.

An object of this invention is to provide apparatus including an ejector for removing from tanks the residual gases and also the liquid residues.

25 In using the ejector, it is undesirable, so as to prevent any damage to the tanks, to apply a higher vacuum than that equal to a water column of a few meters. By using the device according to the invention it is even 30 possible, with the aid of a very low vacuum to also remove the liquid residues from the tanks.

In applying the invention it is possible, under the conditions described, to rapidly remove the liquid residues without it being necessary to open the closing cover of the tanks. With the aid of the device according to the invention, the liquid is first sucked up with the aid of the ejector to a certain height 40 in the suction pipe. Then by suddenly admitting steam pressure into the suction pipe, the liquid is forcibly driven out of the suction pipe and immediately after the ejector is again put in operation, then, owing to the great speed with which the air flows in, a whirling motion is set up around the suction mouth in consequence of which "a mixture of liquid and air" is formed which is carried away through the ejector. In most cases, for 45 instance, the ship is in a harbour, it will be impossible to eject the sucked up liquid in this manner into the open. This would be 50 too dangerous and it will be generally neces-

sary for the benzine to be gasified and "neutralized" by steam.

The mixture of liquid and air sucked up in the manner above described can be removed by the ejector into a special container in which the steam separates from the liquid and the liquid is left behind.

55 If the liquid collected in the container is to be gasified and "neutralized" by the steam, then, it can be brought back into the suction pipe through a pipe which connects the container with the suction pipe during the suction process (when the connection between ejector and container is interrupted) through a specially devised arrangement for the purpose in a finely divided condition and conducted into the open with the gas sucked up 60 from the principal tank through the ejector.

65 The invention is illustrated by way of example in the accompanying drawing.

Fig. 1 shows the complete arrangement. Fig. 2 shows the arrangement on a smaller 70 scale fitted on a tank ship.

75 Figs. 3, 4 and 5 are similar longitudinal sections through the control valve, and illustrating the several operative portions thereof.

80 In the arrangement illustrated in the drawing, 1 is the ejector, 2 is the suction pipe, which ends at a short distance above the bottom 3 of the ship-tank and is fitted with a suction mouthpiece 4. The pipe for the admission of the steam is indicated by 5, whilst 6 is the discharge outlet.

85 Between the nozzle of the ejector and the discharge outlet 6 there is arranged a cock or rotary valve 7. By means of the said cock the following connections can be established.

90 a. A free outflow of the steam coming from the ejector and of the gases into the outer atmosphere.

b. Complete closing of the steam outlet in 95 which case, by the admission of steam into the ejector, the suction pipe 2 is brought under steam pressure.

c. The steam coming from the ejector or the liquid carried away is directed downwards 100 in the cock 7 and discharged into a special container 8 which will be referred to later and in which the liquid remains, whilst the gases escape through the outlet pipe 9.

105 Now, if, in a tank, the suction pipe is immersed in the liquid residue and it is there-

fore impossible to free the said tank from inflammable gases, the following procedure is adopted:

5 The cock or rotary valve 7 is turned rapidly through the three successive positions hereunder indicated:

10 *Position a.*—Where the outlet of the ejector is open and the liquid under the influence of the outflowing steam is sucked up to a certain height in the suction tube 2.

15 *Position b.*—Where the outlet from the ejector is closed and consequently the steam under pressure flows into the suction pipe 2, drives out the liquid therein contained and the latter spreads on the slanting bottom of the tank.

20 *Position c.*—Where the steam can again flow out of the ejector, but where it is led away downwards into the special container 8.

25 When the cock is moved to this position, a vacuum is suddenly produced in the suction pipe 2, in consequence of which a powerful current of air and gas, which carries away a large quantity of liquid, is created and the closing of the suction pipe by the liquid is prevented. Then, the sucked up air or gas and liquid mixture, after it has been carried away through the ejector, is conveyed together with the ejector steam into the container 8. The liquid remains in the container 30 whilst the steam and the gases carried away with it are conveyed into the open by the outlet pipe 9 provided as above.

35 In cases where a considerable quantity of liquid is present in the tank which may stop the suction pipe at the lower end, it is necessary to repeat the process above described. Very large quantities of liquid are conveyed in this manner through the suction pipe into the container 8.

40 These liquid residues sucked up from the bottom of the tank are usually of little value and are of small commercial importance.

45 In most cases it will, therefore, be preferred to gasify these residues with the others. This can be effected by bringing back during the suction of the gases, through the ejector into the suction pipe, the liquid in the container 8 through an atomizer 24, provided in the pipe 10 (which pipe connects the container 8 with the suction pipe 2) and conveying it into the atmosphere with the gases sucked up from the main tank.

55 The cock or rotary valve which serves to produce the aforesaid connection between the suction pipe 2 and the container 8 or the outlet pipe 6 is represented on a larger scale in Figs. 4, 5, 6. The casing of this cock is indicated by 7, whilst 11 is the actual plug of the cock, the upper extension of which 12, by means of a stuffing box 13 is carried through the outer wall 7 and connected with a hand lever 14 with which the rotary plug or cock 11 is brought to the different positions. For securing the correct position, the lever 14 is provided with a locking pin 16 provided

with a head 17 and a spring 15. The other end of said pin 16 engages corresponding holes or depressions 18 in the body 7 of the rotary valve, so that the correct position is secured in the different working stages. The 70 valve casing 7 is provided with flanges 19 for connecting the same between the ejector 1 and the discharge outlet 6. The three sectional views illustrate the valve casing in the same relative position as in Figs. 1 and 2, 75 i. e., with the ejector arranged at the left of the valve. Position *a* of the valve is illustrated in Figs. 1 and 4; position *b* is illustrated in Fig. 3, and position *c* is illustrated in Figs. 2 and 5.

80 The discharge of residues is initiated by turning the valve into the position shown in Fig. 4, the steam passing through the central passage 22 of the valve, and discharging through outlet 6. If liquid residues are 85 present in such quantity that they cannot be lifted to the height of the ejector, the valve is then turned through 90°, as shown in Fig. 3, and steam is directed into the suction pipe 2 to forcibly eject the liquid therefrom and 90 form a froth at the suction mouthpiece 4. The valve is then returned to the initial position to reduce the pressure within pipe 2. A mixture of liquid and gases will be lifted by the suction and discharged from outlet 6 as 95 indicated in Fig. 1. When the valve is turned into the position shown in Fig. 5, the steam, liquid and gases leaving the ejector 1 are diverted downwardly by the curved wall 20 100 of the valve, and discharged through outlet 21 of the valve into the liquid separator or trap 8. The liquid is retained within the trap or is returned to the suction pipe 2, while the gases and vapors pass out through outlet pipe 9, as shown in Fig. 2.

105 Let it be observed that the pipe 10 between the container 8 and the suction pipe 2 which contains the atomizer 24 can be suitably provided with a stop cock 23. The container 8 can also be arranged laterally in relation to 110 the ejector and this arrangement may be adopted without departing from the fundamental idea.

115 It will be apparent that other gases or vapors may be used in place of steam for operating the ejector, and that the term "steam" is used in the following claims in a descriptive and not a limiting sense.

What we claim is:

1. The combination, with a tank or the like, and a suction pipe and steam ejector for discharging liquid from said tank, of valve means at the outlet side of said ejector for obstructing the normal discharge of steam and gases from said ejector, whereby the steam may be diverted into the suction pipe.

2. In apparatus for removing liquids from a tank or the like, a steam injector having a suction pipe extending into said tank, and a valve at the outlet side of said injector, said

valve having a port therein for placing the normal outlet of said ejector into and out of communication with the atmosphere.

3. In apparatus for removing liquids from 5 a tank or the like, a suction pipe extending into the tank, a steam ejector associated with said pipe and having a discharge outlet to the atmosphere, a liquid separator having an outlet for discharging gases to the atmosphere, and valve means for placing said ejector into communication with said discharge outlet or into communication with 10 said liquid separator.

4. In apparatus for removing liquid residues 15 from tanks or the like, a suction pipe extending to a point adjacent the bottom of said tank, a steam ejector associated with said suction pipe, a liquid separator, and means at the outlet side of said ejector for

controlling the operation of said apparatus, 20 said means comprising a valve casing having an inlet opening connected to the outlet of said ejector, a discharge port opening to atmosphere, a second discharge port opening into said liquid separator, and a valve in said 25 valve casing, adapted to establish one of the three following conditions: a direct discharge of the ejector gases to atmosphere through said first discharge port, a closing of the ejector outlet whereby the steam establishes 30 a super-atmospheric pressure in said suction pipe, and a connection of the ejector outlet to the liquid separator through said second discharge port.

In testimony whereof whereof, we affix our 35 signatures.

JAKOB MULDER.

DIRK CHRISTIAAN ENDERT, Junior.
